UNITED STATES PATENT OFFICE.

JOHN A. MCKINNEY, OF LA JUNTA, COLORADO, ASSIGNOR OF ONE-FOURTH TO JAMES B. PEARCE, ONE-EIGHTH TO FRED A. SABIN, AND ONE-EIGHTH TO CHARLES E. SABIN, ALL OF LA JUNTA, COLORADO.

TYPESETTING MACHINE.

Application filed June 4, 1924. Serial No. 717,852.

To all whom it may concern:

Be it known that I, JOHN A. MCKINNEY, a citizen of the United States, and resident of La Junta, in the county of Otero and State of Colorado, have invented certain new and useful Improvements in Typesetting Machines, of which the following is a specification.

My present invention relates to improvements in typesetting machines of the linotype class wherein matrices and spacers are assembled into a line by the manipulation of the keyboard, and the assembled line is then raised by an elevator to a line delivery carriage.

The object of the invention is to provide a simple and economical device capable of ready attachment to existing machines by which the elevator may be raised by power instead of manually as is customary, such power means being released by a readily movable element within convenient reach of the hand of the operator adjacent the keyboard.

With these and other objects in view, the invention includes the novel features of construction and arrangement and combination of parts hereinafter described and particularly defined by the appended claims.

An embodiment of my invention is illustrated in the accompanying drawings, in which:

Figure 1 is a front elevation of a sufficient portion of such a machine shown as an "Intertype," with my attachment in place, to illustrate the invention.

Fig. 2 is a detail view showing the elevating lever and cooperating parts in side elevation.

Fig. 3 is a detail plan view showing the same parts.

Fig. 4 is an enlarged detail in front elevation showing the two holding and releasing means.

Fig. 5 is a section on line 5—5 of Fig. 4.

Fig. 6 is a transverse section on line 6—6 of Fig. 3 on a slightly larger scale.

Figs. 7 to 11, inclusive, are detail views.

Referring by reference characters to these drawings, the numeral 1 designates the elevator which is shown as connected by link 2 to a rearwardly extending arm 3^a on rock shaft 3 which rock shaft is provided with a handle arm 3^b, such arrangement consti-

tuting the usual manual means for raising the elevator, and the rock shaft being journaled in suitable bearings 4 at the front of the keyboard, which is shown conventionally and designated by the numeral 5. 6 designates the arm which operates the line delivery carriage, which arm is fast on a rock shaft 7 journaled in a fixed part of the machine frame and operated by the customary means (not shown).

The usual linotype machine has a horizontal frame part 8 to which the carriage frame part or base 9 is secured at one end by bolt 10, which bolt screws into a threaded opening 9^a in part 9, but does not extend entirely through the same, (see Fig. 6) leaving a threaded recess which I utilize for securing my attachment in place. The said attachment comprises an angular frame or carrying member 11 which may conveniently be struck up from sheet metal and has a horizontal wall 11^a to overlie the top of member 9 provided with an opening (see Fig. 7) for the reception of a bolt 12 which may be screwed into the opening 9^a to secure the attachment rigidly in place. The carrying member 11 also has a vertical wall to abut the side of member 9 and its lower end may be bent over to embrace the under edge of said member 9 in rear of the standard part 9^x, as shown in said Fig. 6.

Pivoted to the rear end of the upper wall 11^a (see Fig. 2) is an arm 13 which extends rearwardly and underlies an arm 14 carried by shaft 7. This arm or lever 14 (as shown in Fig. 10) has a portion formed of double hook shape, comprising a curved part 14^a designed to partially encircle the shaft 7 and a curved part 14^b adapted to hook around the adjacent portion of the arm 6, as shown in Figs. 1 and 3, this arrangement being such that the arm or lever may be readily attached to shaft 7 by merely slipping it around the shaft and with its end 14^b in hooked engagement with the arm 6.

A two-armed lever 15 (Fig. 2) is fulcrumed on an upstanding bracket 16 carried at the rear end of plate 11^a, the rear arm 15^a being connected by one or more tension springs 13^a to the arm 13. The other arm 15^b of the two-armed lever inclines downwardly to the front of the carrying member 11 where it carries a roller 17 which is posi-

tioned beneath and bears with rolling contact, against the under side of the lever 3^a, the roller being preferably grooved to receive the lower edge of lever 3^a and maintain 5 it in contact therewith.

The carrying member 11 has a front wall portion 11^a Figs. 1 and 4, to which is articulated a spring actuated retaining dog 18 (shown in detail in Fig. 9) which is adapted 10 to hook over the end of the lever arm 15^b, this dog being under tension of a spring 19 which tends to hold it in locking position, the dog having an inclined portion 18^a above its engaging shoulder for cooperation with 15 the end of lever arm 15^b, so that downward movement of the latter will throw the dog back against the tension of the spring until its shoulder engages over the lever. Pivoted to the front wall of carrying member 11 is 20 a dog operating arm or lever 20 (shown in detail in Fig. 8) which has a dog engaging part or shoulder 20^a and an angular turned part 20^b which is provided with an eye into which is hooked or inserted the angular 25 turned end of a pull rod 21. This pull rod has attached at its other end a slide member 21^b (Figs. 3 and 11) conveniently in the form of a curved plate member or clip 21^c which is adapted to slidingly engage the 30 shaft 3, said member 21^c carrying a button or projection 21^d adapted to be pressed by the hand of the operator to withdraw the dog from engagement with lever arm 15^b.

From the foregoing description, it is believed 35 the operation of my device or attachment will be clear, but it may be briefly stated as follows:

With the elevator in its lowered position, the arm 6 will be at the extremity of its right 40 hand movement (to the right Fig. 1) and the arm 14 will be held depressed and bearing against the upper side of the lever arm 13, and, the lever arm 15^b being held by the dog, tension is placed on spring 13^a. Supposing 45 now the line of type to have been set and it being desired to raise the elevator, the operator by a momentary lateral pressure on the button, disengages the dog from lever arm 15^b, whereupon the spring 13^a immediately 50 raises the elevator by rocking the two-arm lever 15^a and 15^b, the roller 17 effecting the lifting by bearing upwardly against the under side of arm of lever 3. Thereon the movement of arm or lever 6 to the left in 55 the movement of the line delivery carriage raises the arm 14 from off the arm 13 whereby the tension on the spring 13^a is relieved allowing lever arm 15^b to drop until it is 60 reengaged by the dog. Movement of carriage shift lever to the right (Fig. 1) again places tension on the spring 13^a and the parts are positioned ready for the next elevating operation.

It will be understood that my invention 65 is not limited to any particular form of ma-

chine, as it is applicable to various makes, among which may be mentioned the "Intertype," the "Linotype," and the "International." It will be further understood that my invention is not limited to the precise construction of parts disclosed, as various changes therein may be made without departing from the spirit of my invention. 70

Having thus described my invention, what 75 I claim is:

1. In a machine of the class described, the combination with the carriage operating lever and elevator raising lever, of an arm pivoted to a fixed part of the machine, an arm secured to said carriage operating lever and overlying said first named arm, a two-armed lever fulcrumed on said fixed support, having one arm extending above said second arm, a spring connecting said last 80 named arms, the other arm of said two-armed lever having a part engaging the elevator operating lever, and manually controlled means for locking said two-armed lever against movement. 85

2. In a machine of the class described, the combination with the carriage operating lever and elevator raising lever, of an arm pivoted to a fixed part of the machine, an arm secured to said carriage operating lever and overlying said first named arm, a two-armed lever fulcrumed on said fixed support, having one arm extending above said second arm, a spring connecting said last 90 named arms, the other arm of said two-armed lever having a part engaging the elevator operating lever, and manually controlled means for locking said two-armed lever, said means comprising a spring actuated dog for engaging said two-armed lever, and manually controlled means for actuating said dog. 100

3. In a machine of the character described, the combination with the carriage operating lever and elevator raising lever, of a supplemental lever articulated on a fixed pivot, and having a part for engaging said elevating lever, momentarily releasable means for locking said supplemental lever against movement, a spring for actuating said supplemental lever, and means whereby the movement of said carriage operating lever alternately stores power in and releases said spring. 110

4. In a machine of the character described, the combination with the carriage operating lever and elevator raising lever, of a supplemental lever articulated on a fixed pivot, and having a part for engaging said elevating lever, momentarily releasable means for locking said supplemental lever against movement, a spring for actuating said supplemental lever, and means whereby the movement of said carriage operating lever alternately stores power in and re- 120

leases said spring, said means comprising a lever arm articulated below said supplemental lever, and connected thereto by said spring, and an arm connected with said carriage operating lever and overlying said lever arm.

5. The apparatus of claim 4 in which the overlying arm has a double hooked portion adapted to be merely hooked around the carriage operating arm and its actuating shaft.

6. Apparatus according to claim 4, in which the two-armed lever and lever arm and controlling dog are supported on a car-

rier member adapted to be bolted to a frame 15 part adjacent the keyboard.

7. Apparatus according to claim 4, in which the manually controlled locking comprises a spring pressed dog, a dog releasing lever, and a pull rod connected to said dog releasing lever, said pull rod having a part to slidably clip on the shaft of the elevator raising lever in front of the keyboard, and having a hand engaging projection.

In testimony whereof, I affix my signature.

JOHN A. MCKINNEY.
